UNITED STATES PATENT OFFICE.

AUSTIN S. HOUCK, OF BEDFORD, IOWA.

PLANTER.

SPECIFICATION forming part of Letters Patent No. 248,180, dated October 11, 1881.

Application filed August 18, 1881. (No model.)

To all whom it may concern:

Be it known that I, AUSTIN S. HOUCK, of Bedford, in the county of Taylor and State of Iowa, have invented certain Improvements in 5 Corn-Planters; and I hereby declare the following to be a full, clear, and exact description thereof, reference being had to the accompanying drawings, making part of this specification, in which—

10 Figure 1 is a perspective view of my improved planter. Fig. 2 is a plan view. Fig. 3 is a longitudinal-section view on the line x - x of Fig. 2. Fig. 4 is a detail to be referred to.

15 My invention relates to that class of corn-planter wherein two listing-plows are secured to a frame mounted on wheels and provided with the necessary appliances for draft purposes.

20 My invention consists in certain details of construction and combinations of devices, as hereinafter described and specifically claimed.

25 In order that those skilled in the art may make and use my invention, I will proceed to describe the manner in which I have carried it out.

In the said drawings, $A A$ are the main timbers of the frame, mounted on axle a and wheels $B B$, and provided with a driver's seat, C . Across the frame, and through the front 30 ends of the timbers $A A$, extends a bar, b , the ends of which project out beyond the central line of the peripheries of the wheels B .

35 On the extreme ends of rod b are journaled the beams $E E$ of two listing-plows, $F F$, where they are secured by nuts $d d$. Short metal sleeves $e e$ and bearing-nuts $f f$ are interposed between the beams and the timbers $A A$ on bar b , so that the plows are maintained in a position directly in front of the wheels.

40 Midway between the timbers A , on the bar b , is pivoted the tongue G , having a bifurcated end. Between the end of the tongue and the timbers A metal sleeves $g g$ surround the bar b and prevent the tongue from changing position laterally.

45 Inside the bifurcated end of the tongue and around bar b , is journaled one end of a bent ad-

justable clevis, H , which passes downward and forward, and then upward, ending in a square loop, l , which is larger vertically than the 50 tongue and surrounds it, so the tongue has a free vertical play in it. The clevis H is provided with a series of holes, $i i$, for adjusting purposes, as hereinafter described. After the plow-beams $E E$ pass the point where 55 they are secured to the ends of bar b they are bent sharply in toward the central clevis, H , and secured thereto by means of the bolt h , which passes through their ends and through one of the holes i in the clevis. 60

A rod, I , having a curved bifurcated end clasping the clevis at n , passes rearwardly to the axle, where it is pivoted to a crank-arm, o , projecting from a sleeve, K , which surrounds the axle, and is provided with a bent lever, p , 65 which is within reach of the driver. By throwing lever p forward the bar or rod I forces the clevis upward, and with it the ends of the beams, thereby throwing the points of the listing-plows upward more or less, as may be desired. 70

The double-tree is to be attached to the clevis H by means of one of the holes $i i$.

Having thus described my invention, what I claim as new, and desire to secure by Letters 75 Patent, is—

1. In a planter, the pair of listing-plows provided with beams E , bent forward of the wheels and their ends brought together at the center, in combination with the bar b , to the ends of 80 which the beams are pivoted, the tongue G , having a bifurcated end, the central bent clevis, H , provided with a loop, l , through which projects the tongue, and sleeves e and g , all constructed, arranged, and operated as set 85 forth.

2. The bent clevis H , rod I , and lever P , in combination with the loose sleeve K on the axle, and provided with crank-arm o , for the purpose set forth.

AUSTIN S. HOUCK.
